CLAIM

I claim the ornamental design for a model vehicle spoiler, as shown and described.

DESCRIPTION

FIG. 1 is an upper, left, front perspective view of a model vehicle spoiler showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof;

FIG. 8 is an upper, right, rear perspective view thereof;

FIG. 9 is a lower, left, front perspective view thereof; and,

FIG. 10 is an upper, left, front perspective environmental use view of the model vehicle spoiler.

In the drawings, the broken lines illustrate portions of the model vehicle spoiler that form no part of the claimed design; whereas, the broken lines in the environmental use drawing additionally depict environmental subject matter and are provided for the purposes of illustrating environmental use, structure, and context, and also form no part of the claimed design.
